UNITED STATES PATENT OFFICE.

FRANK E. BARNICKLE, OF TIERRA BUENA, CALIFORNIA.

TOBACCO-PIPE PROTECTOR.

1,103,163.

Specification of Letters Patent. Patented July 14, 1914.

Application filed July 3, 1913. Serial No. 777,221.

To all whom it may concern:

Be it known that I, FRANK E. BARNICKLE, a citizen of the United States, residing at Tierra Buena, in the county of Sutter, State of California, have invented certain new and useful Improvements in Tobacco-Pipe Protectors; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in tobacco pipes and the object of the invention is to form a protector for said pipe whereby the tobacco when placed in the bowl of the pipe may be tamped or pushed down as desired without the necessity of inserting the finger into the bowl of the pipe against the hot ashes as is now the common usage.

A further object is to provide a means by which the said tobacco may be tamped or pushed down at will and the mechanism for doing this will, at the same time, provide a means for preventing the loss of the tobacco from the bowl of the pipe and also prevent hot or glowing ashes from the tobacco being blown out of the bowl in a wind or under similar conditions. This will avoid a condition which is both disagreeable to the smoker and also dangerous in as much as it is liable to set a fire by reason of the hot ashes coming in contact with inflammable material.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

On the drawings similar characters of reference indicate corresponding parts in the several views.

Figure 1 is a side elevation of a pipe with my improved device shown installed thereon ready for use. Fig. 2 is a sectional view of the bowl of the pipe and of my improved device. Fig. 3 is a top plan view partly in section of my improved device.

Referring now more particularly to the characters of reference on the drawings, the

numeral 1 designates the pipe having the usual bowl 2 adapted to carry the tobacco 3.

My improved device consists of a flat coiled wire 4 having formed as a component part thereof projecting rests or brackets 5 adapted to fit against the edges of the bowl of the pipe. From the center of the flat coil 4 the wire of said coil extends upwardly forming a small spiral spring 6 which normally projects above the flat coil 4 and clear of the tobacco 3. In practice the brackets 5 hold the device in position on the top edge of the pipe, the flat coil 4 resting against the tobacco. Then when it is desired to push down or tamp the tobacco the smoker places his finger against the upwardly projecting coil 6 and presses said coil and incidentally the flat coil 4 downwardly against the tobacco causing it to be tamped or pushed downwardly as desired. Then when the operator's finger is removed from the coil 6, the resiliency or springiness of the wires causes them to spring back into normal position.

My improved device is also adjustable to any sized bowl of pipe due to the fact that the spring construction of the flat coil permits two of the brackets or rests to be inserted in against the inside of the pipe and then the other one pressed inwardly with the hand until it can also fit into the bowl of the pipe. This will hold the device within the pipe by frictional means due to the tendency of expansion of the said spring coil and will not permit the same to drop out of the bowl of the pipe until it is to be removed. It can readily be seen that this will permit the device to be inserted in various sizes of bowls and thus one make of the device may be adapted for use in numerous makes of pipes. Thus as will be seen the device embodies a means for holding the tobacco in the pipe and also a means for tamping or pushing the same down without the necessity of the smoker placing his finger against the hot ashes.

From the foregoing description it will be readily seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention what I claim as new and useful and desire to secure by Letters Patent is:—

5 A device of the character described comprising a wire formed into a flat coil, the outer convolution thereof being formed into projecting rests adapted to engage the upper ends of a tobacco pipe bowl, said wire projecting upwardly from the end of the innermost convolution and being formed into a

10 spiral spring, the uppermost convolution of said spiral spring being of a lesser diameter than said flat coil, as described.

In testimony whereof I affix my signature in presence of two witnesses.

FRANK E. BARNICKLE.
